UNITED STATES PATENT OFFICE

WALTER SILBERMANN, OF KASSEL-HARLESHAUSEN, GERMANY

VENTILATING DEVICE FOR THE INTERIOR OF CLOSED CAR BODIES

Application filed June 20, 1929, Serial No. 372,357, and in Germany April 15, 1929.

The problem of ventilating the interior of closed car bodies, especially such of motor cars, autobusses, dining cars and the like, has up to now not been solved in an actually satisfying manner; only circumstantial and sometimes annoying expediences have been brought forth. Matters are particularly bad as regards the ventilation of small motor cars during the drive, in that opening one of the windows even only a little gives rise to a very disagreeable, as well as dangerous draught.

The present invention relates to a very practical solution of the problem stated. It consists of a bent tube which is supported in one of the walls of the car body and is turnable therein, and is enlarged at its outer end so as to resemble a hopper. This enlarged end, or the hopper, can be turned rearwardly during the drive so that the outer air exerts a sucking action upon said tube and, thus, also upon the interior of the closed car body, but, also another position of that ventilation tube may be chosen. At the inner end of the ventilation tube is a small hand wheel for turning it, and also means for fixing the tube in its adjusted position are provided.

Generally, said ventilation tube terminates in the interior of the car practically at the inner surface of the respective wall, it being understood that there are provided the means for turning the tube and for fixing it in its position, but it is also possible to extend the tube inwardly and bend this end counter to the outer end, the entire tube resembling then somewhat an S. This inner end may be directed forwardly, and its end may also be enlarged so as to resemble a hopper, like the outer tube end. If such an inner extension of the ventilation tube is provided, a separate hand wheel for turning the tube may be dispensed with.

The invention is illustrated diagrammatically and by way of example on the accompanying drawings in which

Figure 1 is a perspective illustration of a ventilating device designed according to this invention, and

Figure 2 is a plan of the same, partly in section.

On the drawings, 1 denotes a side-wall of the car body, and 2 is a bent outer tube which is enlarged at its end so as to form a kind of hopper 3. 5 denotes the annular place of junction between the parts 2 and 3. The side-wall is in this example that on the right side of the car body and the tube is directed counter to the direction of the drive at the time being. The tube may, however, be turned by any desired number of degrees, even by 180, so that its position is completely reversed. There is in this example a bent tube 4 with a hopper 15 provided also within the car body and directed counter to the tube 2 with its hopper 3. The two tubes may be rigidly connected with one another so as to be simultaneously turnable, but, if preferred, each may be separately turnable. This is the case in the example shown:

When the hopper is in the position shown in Fig. 1, in which case the car is running counter to the direction indicated by the arrow P, that is to say, the air is passing along the car in the direction of the arrow P, air is entering into the hopper 3 through said aperture 5 and withdraws air from the interior of the closed car body through the tube 2, or through the tubes 2 and 4 respectively.

For the purpose of turning the outer ventilation tube a hand-wheel 6 is provided inside the car body. It is connected with a flange 7 of said tube, and in the rim of this flange are provided recesses 8 which co-operate with a lug 11 projecting forth from a lever 10 subjected to the action of a tension spring 9, as shown in Fig. 1.

The inner tube 4 is provided with a collar 16 having recesses 12 co-operating with a lug 14 of a lever 13 which is also subjected to the action of said spring. This latter is attached at one of its ends to the lever 10 and at the other end to the lever 13.

I wish it to be understood that I do not limit myself to the details of the ventilation device, especially as regards the means for fixing the one or the other tube in its adjusted position. It is also not indispensably requisite that the outer ventilation tube or the inner one are bent in the manner shown in the drawings merely by way of example. If pre-

ferred, the one or the other tube or both may be straight, and it is also possible to provide means, for instance a valve of any suitable type, or a slide or a cock, by which the communication between the interior of the car body and the outer air can be completely interrupted. Finally, the device may be attached to any one of the sides of the car body, or to the rear wall, or to the top, as desired or preferred.

I claim:

1. A ventilating device for the interior of closed car bodies, comprising, in combination with any of the lateral car body walls and an opening in the same, an annular member inserted into said opening and fixed to the respective wall; a tube, one end of which is turnably located in said annular member and the body portion of which is so bent that its other end extends practically parallel to that wall outside the same; an adjustable hand wheel secured to the inner end of said tube; means for fixing said wheel in its adjusted position; another tube, one end of which is turnably coupled with the inner end of the first-mentioned tube and the body portion of which is so bent that its other end extends practically parallel to the said car body wall inside the car; and means for fixing said other tube in its adjusted position.

2. A ventilating device for the interior of closed car bodies, comprising, in combination with any of the lateral car body walls and an opening in the same, an annular member inserted into said opening and fixed to the respective wall; a tube, one end of which is turnably located in said annular member and the body portion of which is so bent that its other end extends practically parallel to that wall outside the same; an adjustable hand wheel secured to the inner end of said tube; means for fixing said wheel in its adjusted position; another tube, one end of which is turnably coupled with the inner end of the first-mentioned tube and the body portion of which is so bent that its other end extends practically parallel to the said car body wall inside the car; an adjusting flange affixed to said other tube in front of said hand wheel and having recesses in its periphery; a hand lever supported inside the car body near said flange; another hand lever also supported inside the car body near said adjusting flange; and a projection provided at said other hand lever in such a position as to be able to engage any of the recesses of the said adjusting flange.

3. A ventilating device for the interior of closed car bodies, comprising, in combination with any of the lateral car body walls and an opening in the same, an annular member inserted into said opening and fixed to the respective wall; a tube, one end of which is turnably located in said annular member and the body portion of which is so bent that its other end extends practically parallel to that

wall outside the same; an adjustable hand wheel secured to the inner end of said tube; means for fixing said wheel in its adjusted position; another tube, one end of which is turnably coupled with the inner end of the first-mentioned tube and the body portion of which is so bent that its other end extends practically parallel to the said car body wall inside the car; an adjusting flange affixed to said other tube in front of said hand wheel and having recesses in its periphery; a hand lever supported inside the car body near said flange; another hand lever also supported inside the car body near said adjusting flange and extending parallel to the first-mentioned hand lever at the opposite side of the said hand-wheel; and a helical tensile spring connecting the said two levers with one another, substantially as set forth.

In testimony whereof I affix my signature.

WALTER SILBERMANN.
